(57) **CLAIM**

The ornamental design for a day cab road tractor with drag-reducing film system, as shown and described.

DESCRIPTION

The present application is potentially related to U.S. patent application Ser. No. 29/404,017 also entitled Road Tractor with Drag-Reducing Film System to inventors Peter Salaverry and Richard Wood, filed Oct. 13, 2011.

FIG. 1 is a perspective view of a day cab road tractor with drag-reducing film system showing our new design, portions of the day cab road tractor shown in broken line form no part of the claimed design.

FIG. 2 is an enlarged view of a portion of FIG. 1 to more clearly illustrate the films thickness and holes punched there through.

FIG. 3 is a side view thereof, the opposite side being a mirror image thereof.

FIG. 4 is a front view thereof; and,

FIG. 5 is a top view thereof.
